This application is related to the following Applications: Design Application “C/D Multi-Powr Cell Display Package, Two Embodiments”, Ser. No. 29/172,626; Design Application “AA/AAA Multi-Power Cell Display Package, Four Embodiments”, Ser. No. 29/172,541; and Utility Application “Apparatus for Displaying Battery Products”, Ser. No. 10/318,956.

FIG. 1 is a front perspective view of an embodiment of an assembled 9 volt multi-power cell display package, in accordance with the present invention.

FIG. 2 is a rear perspective view of an embodiment of an assembled 9 volt multi-power cell display package, in accordance with the present invention.

FIG. 3 is an exploded front plan view of an embodiment of a 9 volt multi-power cell display package, in accordance with the present invention.

FIG. 4 is an exploded rear plan view of an embodiment of a 9 volt multi-power cell display package, in accordance with the present invention.

FIG. 5 is an exploded top view of an embodiment of a 9 volt multi-power cell display package, in accordance with the present invention.

FIG. 6 is an exploded bottom view of an embodiment of a 9 volt multi-power cell display package, in accordance with the present invention; and,

FIG. 7 is an exploded right side elevation view of an embodiment of a 9 volt multi-power cell display package, in accordance with the present invention. The left side view is a mirror image of the right side view and is not shown.

The broken lines showing the environment in the Figures are for illustrative purposes only and form no part of the claimed design.
